CLAIM

I claim the ornamental design for a shoulder pad mounted clear helmet, as shown and described.

DESCRIPTION

FIG. 1 is a front view of a shoulder pad mounted clear helmet showing my new design;

FIG. 2 is a rear view thereof;

FIG. 3 is a top view thereof;

FIG. 4 is a bottom view thereof;

FIG. 5 is a right side view thereof, the left side being a mirror image; and,

FIG. 6 is a side view of FIG. 5 showing the unclaimed portion of the helmet in an open position.

The details shown in broken lines are for illustrative purposes only and form no part of the claimed design.
